UNITED STATES PATENT OFFICE.

FLETCHER D. HALLOCK, OF WILKINSBURG, PENNSYLVANIA, ASSIGNOR
TO WESTINGHOUSE ELECTRIC & MANUFACTURING COMPANY, A COR-
PORATION OF PENNSYLVANIA.

CONTROLLING MEANS FOR ELECTRIC MOTORS.

No. 838,021.

Specification of Letters Patent.

Patented Dec. 11, 1906.

Application filed June 2, 1905. Renewed January 20, 1906. Serial No. 297,042.

To all whom it may concern:

Be it known that I, FLETCHER D. HALLOCK, a citizen of the United States, and a resident of Wilkinsburg, in the county of Allegheny and State of Pennsylvania, have invented a new and useful Improvement in Controlling Means for Electric Motors, of which the following is a specification.

My invention relates to controlling means for dynamo-electric machinery, and particularly to means that are adapted to effect relatively wide motor speed variations in either direction of rotation by a combined reversing-drum and a field-resistance regulator.

The object of my invention is to provide means for adjusting the amount of resistance included in the field-circuit of a motor without changing the predetermined arc of rotation or the normal action of a single controlling-handle by which a movable contact-arm of the field resistance and the switching-drum are simultaneously actuated.

Controllers heretofore employed for governing electric motors that were utilized for driving machine-tools or for similar purposes requiring wide speed variations usually embodied a reversing and switching drum to which a contact-arm was rigidly attached to engage a plurality of field-rheostat contacts as the drum was driven through a predetermined arc of rotation by an operating-handle or other equivalent means. With this arrangement it was necessary to reconnect the resistance or replace it entirely in order to effect any adjustment of the field resistance to suit special conditions or to adapt the controller to any size of motor other than that for which it was designed.

In order to make a more flexible arrangement which shall obviate the aforesaid objections and limitations, I have devised a controller having a field-rheostat the contact-arm of the stationary member of which is greater than that of the drum rotation and one of the contact members of which is so adjustable upon its support that the maximum amount of resistance included in the field-circuit may be varied to suit any given case.

In the accompanying drawings, Figure 1 is a side elevation, with the case partially removed, of a controller constructed in accordance with my invention. Fig. 2 is a detail view of one of the controller parts. Fig. 3 is

a transverse sectional view of the controller, and Fig. 4 is a diagrammatic view of an electric-motor-control system embodying my invention.

Referring first particularly to Fig. 4, an electric motor 1 is supplied with energy from a line 2 through a controller 4 and is provided with a shunt field-magnet winding 5, that may be regulated by a variable resistance 6. The fingers of the controller 4 engage the drum 4^a in a plurality of positions a, b, c, d, e, f, g, h, i, j, k, l, and m when the drum is rotated in one direction and in a plurality of similar positions r, s, t, u, v, w, and x when the drum is rotated in the opposite direction. The variable resistance 6 is provided with a plurality of taps that lead to stationary contact-terminals 7 to 39, inclusive, which are successively engaged by an adjustable contact-arm 41, with which the controller-drum is provided. When the controller-fingers engage the drum in the "off" position z, the contact-arm 41 engages the field-resistance contact 20, and as the drum is moved so that the fingers occupy position a, which is the starting position for forward rotation of the motor 1, the arm 41 engages successively the contacts 21, 22, and 23. When the fingers occupy position a, energy is supplied from the positive line-terminal 3 through a conductor 42, contact-finger 43, contact-ring segments 44 and 45, finger 46, conductor 47 to one armature-terminal 48 of the motor 1. From the other armature-terminal 49 of the motor 1 the circuit is completed through a conductor 50, contact-finger 51, contact-ring segments 52 and 53, finger 54, resistance 55, finger 56, and conductor 57 to the negative line-terminal 2. The ring-segment 45 is also connected to the contact-arm 41, which is in engagement with the field-resistance contact-terminal 23, so that the circuit is completed by this path through a small portion of the resistance 6, the conductor 58, and the field-magnet winding 5 to the negative line-terminal 2. Thus when the controller is in this position the resistance 55 is connected in series with the armature-circuit, and the small portion of the resistance 6 is connected in series with the field-magnet winding 5, so that the motor 1 may be started with a strong field and without excessive armature-currents. As the controller-drum is

moved to engage the fingers in position *b* the arm 41 moves to contact-terminal 26 and the contact-finger 56 engages ring-segment 59, so that a circuit is completed from the ring-segment 53, through the ring-segment 59, contact-finger 56, and conductor 57 to the line-terminal 2, thereby short-circuiting the resistance 55, which is cut out as the controller moves to the position *c*, since the contact-finger 54 is then moved out of engagement with the contact-ring segment 53. As the controller-fingers occupy the remainder of the positions in this direction from *d* to *m*, inclusive, the motor connections remain the same, and the contact-arm 41 successively engages contacts 28 to 37, inclusive, thereby gradually introducing the resistance 6 into the field-circuit of the motor, which weakens the field and increases the speed of the motor.

20 When the controller-fingers occupy the last position *m*, if the speed of the motor is still low the arm 41 may be so adjusted as to cut in a greater amount of the resistance 6 as the drum moves to engage the fingers from position *z* to position *m*, or if the speed is too high the arm 41 may be adjusted in the opposite direction, so as to cut in a less amount of resistance. For example, the arm may be so adjusted as to engage the contact-terminals 22 to 39 or it may be so adjusted as to engage the terminals 18 to 35. When the controller-fingers occupy the position *r*, which corresponds to the position *a*, the resistance 55 is included in the armature-circuit as before; but the direction of current through the armature is reversed, energy being supplied from the finger 43, through ring-segments 60 and 61, to armature-terminal 49 and from armature-terminal 48, through conductor 47, finger 62, contact-ring segments 63, 64, and 65, finger 54, resistance 55, finger 56, and conductor 57, to the negative line-terminal 2. When the controller-drum moves to engage the fingers in positions *s* and *t*, the resistance 55 is first short-circuited and then cut out, and as the positions *s*, *t*, *u*, *v*, *w*, and *x* are occupied the contact-arm 41 engages contacts 16 to 7, which are connected to the contacts 24 to 32, and consequently introduces portions of the resistance 6, as before. The contacts 16, 17, 18, 19, 20, 21, 22, 23, and 24, which are engaged by the contact-arm 41 while the controller-drum moves to engage the fingers from the off position to the position *a* or the position *r*, are connected together, so that the resistance 6 is gradually introduced into the field-circuit regardless of the adjustment of the arm 41.

As shown in Figs. 1, 2, and 3, the controller-drum 4^a is actuated by an operating-handle 66 in the usual manner, and adjustably attached to its lower end, by means of a ring-shaped body portion 67, which movably engages a corresponding cylindrical portion 68 on the controller-drum, is the radial contact-

arm 41, the ring portion 67 of the contact member being clamped to the portion 68 by means of set-screws 69. The contact-terminals 7 to 39 are mounted upon an insulating-plate 70, which is rigidly fixed in a plane substantially perpendicular to the axis of rotation of the drum and are annularly disposed thereon, so that they may be engaged by the contact-arm 41 as the controller-drum is rotated. Each contact-terminal is provided with set-nuts 71 or equivalent devices, by means of which the resistance-leads may be attached thereto. By loosening the set-screws 69 the contact-arm 41 may be circumferentially adjusted upon the drum in order to effect the introduction of a greater or less amount of resistance as the controller-drum is actuated through a predetermined arc of rotation, as hereinbefore set forth.

Although I have shown and described a specific arrangement as a means to an end, I desire it to be understood that my invention is of such scope as to cover and include all controllers however varied as to size, form, and arrangement of parts, in which either of two co-operating contact members is adjustable upon its support along the path of movement of the movable member in such manner and to such degree that the hereinbefore-specified result may be secured.

I claim as my invention—

1. In a controller for dynamo-electric machinery, the combination with a rotatable, contact-carrying drum and a stationary contact-carrying plate substantially perpendicular thereto, of a circumferentially-adjustable, radially-disposed contact-arm that is mounted upon said drum to engage the contacts on said plate.

2. In a controller for an electric motor, the combination with a rotatable, contact-carrying drum that is limited to a predetermined arc of rotation and is provided with a circumferentially-adjustable contact-arm, of a plurality of fixed contact-terminals that may be engaged by said contact-arm.

3. The combination with a plurality of fixed contact-terminals, of a contact-arm that is rotatably mounted and limited to a predetermined arc of rotation and is radially disposed to engage said fixed contact-terminals, and means for circumferentially adjusting said contact-arm.

4. The combination with a rotatable, contact-carrying drum that is limited to a predetermined arc of rotation and a plurality of fixed contact-terminals that are in a plane which is substantially perpendicular to the axis of said drum, of a radially-disposed contact-arm mounted on said drum which engages said fixed contact-terminals and is circumferentially adjustable upon the drum.

5. The combination with a plurality of fixed contact-terminals arranged substantially in an arc of a circle, of a rotatably-

- mounted contact-arm which may engage said contact-terminals through a predetermined arc of rotation and is circumferentially adjustable in respect to said contacts.
5. In a controller for dynamo-electric machinery, the combination with a rotatable, contact-carrying member that engages a plurality of fixed contact-terminals and is limited to a predetermined arc of rotation, and a fixed contact-carrying plate which is substantially perpendicular to the axis of said rotatable member, of a radially-disposed contact-arm that engages the fixed contacts and is adjustably mounted on said rotatable member.
10. In a controller for dynamo-electric machinery, the combination with a rotatable, contact-carrying drum that is limited to a predetermined arc of rotation, and a field-rheostat adjacent to one end thereof, of a contact-arm that is carried by said drum to engage a plurality of contact-terminals on said rheostat and is circumferentially adjustable in respect to said drum.
15. 8. The combination with a rotatable switch-drum and a plurality of fixed, engaging contact-fingers therefor, of an adjustable and radially-mounted contact-arm, and a plurality of contact-terminals located substantially in the arc of a circle and in the plane of rotation of the contact-arm.
20. 9. The combination with an electric motor and a switching and controlling drum therefor, of a field-resistance-regulating device that comprises an adjustably and radially mounted contact-arm and a plurality of contact-terminals located substantially in the arc of a circle in the plane of rotation of the contact-arm.
25. 10. In a controller, the combination with a rotatably-mounted contact-carrying member that is limited to a predetermined arc of rotation, a resistance, and a plurality of fixed contact-terminals for said resistance mounted in the arc of a circle on a plane substantially perpendicular to the axis of the rotatable member, of a radial contact-arm which is adjustably mounted on the said contact-carrying member and engages said fixed contact-terminals.
30. 11. In a control system, the combination with an electric motor, a switching and reversing controller therefor and a field resistance that is provided with a plurality of steps for use therewith, of means for regulating the amount of resistance included in the field-circuit at any predetermined point in the controller operation.
35. 12. In a control system, the combination with an electric motor, a switching and reversing controller and a field resistance for use therewith, of a contact-arm that is adjustably mounted on the controller-drum and is actuated therewith to increase the resistance in the field-circuit as the controller successively occupies a plurality of predetermined positions.
40. 13. In a controller for electric motors, the combination with a set of contact-fingers and a coöperating movable member, of a subdivided resistance having a set of contact-terminals and a contact-arm that is mounted upon said movable member and is adjustable thereon.
45. 14. In a controller, the combination with a set of contact-fingers and a coöperating movable member, of a rheostat comprising a resistance-body, a set of contact-terminals connected to different points therein, and a contact-arm that is adjustably mounted on said movable member.
50. 15. In a controller for dynamo-electric machinery, the combination with a movable, contact-carrying member and a set of coöperating fingers, of a plurality of stationary contact-terminals and a contact-arm that is adjustably mounted on said movable member to engage the fixed contact-terminals.
55. 16. In a controller for electric motors, the combination with a rotatable contact-carrying drum that is limited to a predetermined arc of rotation and is provided with a contact-arm, of a normally stationary contact member comprising a plurality of contact-terminals in position to be engaged by said contact-arm and means for adjusting one of said contact members upon its support relatively to the other.
60. 17. The combination with a rotatable contact-carrying drum that is limited to a predetermined arc of rotation, and a contact member comprising a plurality of contact-terminals that are in a plane which is substantially perpendicular to the axis of said drum, of a radially-disposed contact-arm mounted on said drum to engage said contact-terminals, and means for rotatively adjusting one of said members upon its support with reference to the other.
65. 18. In a controller for dynamo-electric machines, the combination with a rotatable contact-carrying drum that is limited to a predetermined arc of rotation, a rheostat and a normally stationary contact member comprising a set of contact-terminals disposed adjacent to one end of said drum, of a contact member that is carried by said drum to engage said contact-terminals, and means for adjusting one of said contact members upon its support with reference to the other.
70. 19. The combination with a rotatable switch-drum and a plurality of stationary contact-fingers to engage therewith, of a contact-arm supported by said drum, a normally stationary contact member comprising a plurality of contact-terminals that are disposed substantially in the arc of a circle and in the plane of rotation of the contact-arm,

and means for adjusting one of said contact members upon its support in the contact-path.

20. The combination with an electric motor and a switching and controlling drum therefor, of a field-resistance-regulating device that comprises a radially-mounted contact-arm and a normally stationary contact member comprising a plurality of contact terminals disposed substantially in the arc of

a circle in the plane of rotation of the contact-arm, and means for rotatively adjusting one of the contact members upon its support with reference to the other.

In testimony whereof I have hereunto subscribed my name this 31st day of May, 1905.

FLETCHER D. HALLOCK.
